Primary Examiner — Garth Rademaker(74) *Attorney, Agent, or Firm* — Frost Brown Todd LLC**CLAIM**

The ornamental design for a fan with shroud, as shown and described.

DESCRIPTION

FIG. 1 is a front perspective view of a fan with shroud, showing our new design, omitting the front and rear grille pieces for ease of disclosure;

FIG. 2 is a rear perspective view thereof;

FIG. 3 is a front elevational view thereof;

FIG. 4 is a back elevational view thereof;

FIG. 5 is a left elevational view thereof;

FIG. 6 is a right elevational view thereof;

FIG. 7 is a top plan view thereof;

FIG. 8 is a bottom plan view thereof;

FIG. 9 is a front perspective view thereof, showing the front grille and omitting internal elements for ease of disclosure;

FIG. 10 is a rear perspective view thereof, showing the rear grille and omitting internal elements for ease of disclosure; FIG. 11 is a front elevational view thereof, showing the front grille and omitting internal elements for ease of disclosure; and,

FIG. 12 is a rear elevational view thereof, showing the rear grille and omitting internal elements for ease of disclosure. The broken lines depict portions of the fan with shroud which form no part of the claimed design.
